UNITED STATES PATENT OFFICE.

ALBERT GOTTSCHALK, OF NEW YORK, N. Y., ASSIGNOR TO NATIONAL PNEUMATIC COMPANY, OF CHICAGO, ILLINOIS, A CORPORATION OF WEST VIRGINIA.

DOOR-OPERATING APPARATUS.

1,168,301.

Specification of Letters Patent. Patented Jan. 18, 1916.

Application filed February 1, 1913. Serial No. 745,587.

To all whom it may concern:

Be it known that I, ALBERT GOTTSCHALK, a citizen of the United States, residing at New York, in the county and State of New 5 York, have invented a certain new and useful Improvement in Door-Operating Apparatus, of which improvement the following is a specification.

This invention relates to motor apparatus 10 for operating doors, and is particularly adapted for use in connection with car doors such as employed on subway, elevated, and suburban railway cars, where the guard or motorman may be positioned at some distance 15 from the doors which must be opened and closed at each station or stop for the discharge and loading of passengers. Where the doors are located at some distance from the guard, as the center side doors of a 20 car in which the guard or operator is at the end of the car, it is sometimes difficult for the operator to see clearly whether or not the door is free to be closed, and it is important to provide a safety means for automatically 25 preventing injury to a person in case one should be struck or caught by the door during its closing movement.

One of the objects of my present invention is to provide improved means for automatically 30 relieving the pressure from the motor when the door encounters an obstruction during its closing movement, as when a person is caught in the door; another object is to automatically reverse the movement 35 of the door; another object is to prevent the slamming or very rapid movement of the door in case it is temporarily forcibly held stationary against the action of the fluid pressure, during its traverse; and another 40 object is to provide means operating automatically to effect an application of the brakes upon the car when the door encounters a person or other obstruction during its closing movement.

In the accompanying drawings: Figure 1 45 is a vertical longitudinal section of my motor apparatus and showing means for automatically relieving the pressure from the closing end; for reversing the movement of the motor; and for causing an application 50 of the brakes on the car when the door, encounters an obstruction; Fig. 2, a side elevation of the same; Fig. 3, a transverse section on the line 3—3 of Fig. 2; Fig. 4, 55 a plan of the rotary valve; Fig. 5, a plan

of the rotary valve seat; Figs. 6, 7, and 8, diagrams showing the rotary valve upon its seat in its three respective positions; Fig. 9, a view illustrating one form of vent valve adapted to be operated by a yielding strip 60 mounted on the jamb of the car door; Fig. 10, an enlarged view of the vent valve indicated in Fig. 9; Fig. 11, a diagrammatic view of a modification including an electromagnet for actuating the vent valve; Fig. 12, 65 a diagrammatic view of another modification illustrating a different form of vent valve device operated by a yielding strip mounted on the car door; Fig. 13, a side view of a car door showing a modified form 70 of yielding strip construction; and Fig. 14, a diagrammatic view of a vent valve device operated by the yielding strip construction shown in Fig. 13.

According to the construction shown in 75 the drawings, the motor apparatus for operating the door comprises a long cylinder, 8, containing a piston having two opposite heads, 9, connected by a rod or rack bar, 10, carrying teeth, 11, meshing with the segmental gear, 12, on shaft, 13, of the rock arm, 14, which may be connected in any suitable and well known manner for actuating the door. For controlling the supply 80 of fluid pressure to the opposite ends of the cylinder, a rotary valve, 15, is mounted on a seat, 16, within a casing, 17, and has a stem, 18, with an arm, 19, for actuating the same. The supply of fluid, such as compressed air, is admitted by pipe, 20, ports, 21 and 22, into the valve chamber, the valve 85 also being provided with a cavity, 23, communicating with port, 22, and other cavities, 28^a and 28^b. In the valve seat are formed large ports, 24 and 25, communicating with opposite ends of the cylinder, 8, restricted ports, 24^a and 25^a, communicating respectively with ports, 24 and 25, and large exhaust ports 29^a and 29^d, and restricted exhaust ports, 29^a and 29^b. 90

For the purpose of shifting the valve automatically to lap or closed position after the piston, 9, has completed its traverse in opening or closing the door, a valve shifting cylinder, 30, is provided containing piston heads, 33, and an intermediate rack bar, 34, meshing with a segmental gear carried by a sleeve, 35, mounted on the valve casing, 17, and provided with lugs, 36, engaging the valve lever, 19. Ports, 31 and 32 leading 95

100

105

110

from the cylinder, 8, at the ends of the traverses of the piston heads, 9, communicate with opposite ends of the valve shifting cylinder, 30. As the piston heads, 33, are not attached to the rack bar, 34, light springs may be employed between the opposite ends of the cylinder, 30, and the respective heads, 33, as indicated in Fig. 2.

When the rotary valve is turned to the position indicated in Fig. 6, for closing the door, the rack bar, 34, and one piston head, 33, are moved to the left, and air or other fluid under pressure is admitted through port, 24, to one end of cylinder, 8, where it acts upon the piston, 9, forcing the same to the right, and turning the door operating arm, 14, to the closed position, as shown in Fig. 1. During this movement, the opposite end of the cylinder, 8, is open to the atmosphere through port, 25, cavity, 28^a, and the restricted exhaust port, 28^b, thereby exerting a cushioning effect upon the piston. As the piston reaches the end of its traverse, the port, 32, is opened, thereby admitting fluid to the valve shifting cylinder, 30, where it operates to move the piston head, 33, and rack bar, 34, back to the middle position shown in Fig. 2. This also operates through the gear, 35, and lever, 19, to turn the valve, 15, back to its normal lap or closed position, illustrated in Fig. 7. By turning the rotary valve to the position indicated in Fig. 8, a similar operation of the apparatus in the opposite direction is produced for opening the door. As thus far described the construction is substantially the same as that shown and described in my prior pending applications Ser. No. 519,432, filed September 24, 1909, and Ser. No. 677,766, filed February 15, 1912.

During the closing movement, the door is sometimes temporarily held stationary or nearly so, either by a person taking hold of the door, or by the door or mechanism sticking, and during this time, a high pressure accumulates upon the motor, which is liable to slam the door very hard when released or when the friction is overcome. In order to prevent this undesirable condition, I may provide a restricted port through which fluid may be admitted very slowly to the opposite end of the main cylinder, 8, when the piston, 9, is moving toward that end. The size of such restricted port must necessarily be so small as to not materially retard the movements of the motor and the door under normal conditions, but when the door is temporarily held stationary, a sufficient pressure may accumulate upon the opposite end of piston, 9; even with the restricted exhaust port open at the same time, to prevent a violent and dangerous movement of the door when it is released. As shown in the drawings, the ports, 90^a and 90^b, in the rotary valve, 15, and the ports,

90^c and 90^d, in the seat, communicating respectively with ports, 24 and 25, are provided for this purpose. When the rotary valve is in its closing position, Fig. 6, at the same time that fluid is being admitted through ports, 24^a and 24, to the left hand end of cylinder, 8, to move the piston, 9, to close the door, fluid is also admitted very slowly through the restricted ports, 90^a, 90^d, and 25 to the opposite end of cylinder, 8. This pressure will not materially retard the movement of the motor and door under normal conditions, as the restricted exhaust port, 29^b, is open at the same time, but if the door should be temporarily held stationary, so that a high pressure is accumulated, there will then be sufficient pressure accumulated in the opposite end of cylinder, 8, to prevent a violent slamming of the door when released. This pressure may also serve to cause a reverse movement of the motor when a relief valve device is employed for exhausting fluid from the closing end of the motor, when the door is obstructed during its closing movement. Ports, 90^b, and 90^c, in the rotary valve and seat perform a like function when the valve is set in its opening position, Fig. 8, for actuating the motor to open the door.

According to another feature of my present invention, I provide an improved safety device for preventing injury to persons accidentally caught in the door when closing, and as shown in the drawings, one form of such a device comprises a yielding strip, 38, mounted upon the door jamb, as indicated in Figs. 1 and 9, in such a manner that when a person or other object is caught between the door and the jamb, the yielding strip, 38, is depressed, and acting through rod, 39, and stem, 41, unseats auxiliary valve, 40, which controls the operation of valve devices for relieving the pressure from the closing end of the motor, for reversing the movement of the motor, and for causing an application of the brakes upon the car, any one or more of which valve devices may be employed as desired. The device for relieving the pressure from the closing end of the motor may comprise a valve, 64, for opening communication from the closing end of cylinder, 8, and port, 72, to the discharge port, 65, said valve being normally held closed by the fluid pressure and a spring, 68, and having a stem operated by a piston, 62, in a cylindrical chamber, 61, to which is connected the pipe, 60, controlled by the auxiliary valve 40. The valve, 40, is normally held seated by means of a spring, 42, and the fluid pressure in the supply pipe back of the valve, but when the valve is opened by the movement of the strip, 38, fluid under pressure flows through pipe, 60, to chamber, 61, where it acts upon piston, 62, and opens the discharge valve, 64. The

size of the discharge opening is sufficient to permit a rapid reduction in pressure in the cylinder, 8, even if the fluid continues to be supplied to the cylinder through the restricted inlet port, 24^a, of the rotary valve, and the door may then be pushed toward its open position if the door lever is at such an angle as permits of this action. When the obstruction is withdrawn from the door, and the valve, 40, closes, the pressure in chamber, 61, immediately escapes around the stem, 41, and the valve, 64, closes. The apparatus then resumes its closing operation automatically as the pressure continues to be admitted through the inlet port, 24, to the cylinder, 8.

In some cases, particularly where the door operating lever occupies a horizontal position, when the door is closed, it is desirable to positively reverse the movement of the motor when a person is caught in the door at the time of closing, and for this purpose, I may provide a valve, 78, controlling communication from supply pipe, 20, and passage, 82, to the passage, 81, leading to the opposite end of cylinder, 8, said valve being seated by a spring, 79, and having a stem actuated by a piston, 77, in chamber, 75, which may be supplied with fluid under pressure through pipe, 60, and passage, 76, when the auxiliary valve, 40, is opened. A check valve, 80, is located in the inlet passage or port, 81, for preventing the escape of pressure from the main cylinder, 8. When the auxiliary valve, 40, is opened, the fluid acting on piston, 77, opens the valve, 78, and admits fluid from the supply, 20, into the opposite end of the cylinder, 8, where it acts on piston, 9, and reverses its movement, thus moving the door away from the person caught. As soon as the supply through the auxiliary valve, 40, is closed the valve, 78, automatically closes as the pressure then readily escapes around the piston, 77, and out at port, 83.

For the purpose of effecting an application of the brakes upon the car and thereby preventing the same from moving at the time that a person is caught in the door, and the auxiliary valve, 40, is opened, a valve, 46, may be employed for controlling a vent port, 45, and be actuated by a piston, 43, in a chamber, 44, communicating with the supply passage, 76. The valve, 46, may control the train brake pipe pressure directly, or may serve as a pilot valve for governing the pressure acting on piston, 51, in chamber, 49, which piston is attached to the main vent valve, 50, for discharging air from the train brake pipe, 53, in order to effect an application of the automatic brake upon the car in the well known manner. Air under pressure in the train pipe, 53, which is normally charged to the desired standard degree, equalizes around the piston, 51, for which

purpose there may be a small perforation through the piston, and together with the force of the spring, 52, holds the valve, 50, normally tightly closed upon its seat. Valve, 46, is also held closed by this pressure which communicates therewith through passage, 48, a light spring, 47, being also employed if desired. It will now be apparent that whenever the auxiliary valve, 40, is opened by a person being caught in the door, the valve, 46, will be opened by the piston, 43, thereby venting the pressure from the back of the piston, 51, and opening the valve, 50. The train pipe pressure is then suddenly discharged to the atmosphere causing the brakes to be applied upon the car according to the well known automatic action of the brake system. This feature of my improvement prevents the train from being inadvertently or prematurely started when a person is caught in a door and might otherwise be dragged along the platform causing very serious injury or loss of life. While the above described valve devices are shown as mounted upon the heads of the cylinder, 8, it will be understood that they may be mounted in separate casings, if preferred, and be connected up with suitable pipe connections.

Various modifications of this feature of my improvement in which the brakes are caused to be applied upon the car when the car door encounters an obstruction in closing, may be made, as shown for instance in Figs. 9 to 14, of the drawings.

According to the construction shown in Figs. 9 and 10, the yielding strip, 38, may be pivotally mounted on the jamb of the door, 55, and operate when compressed by a person being caught in the door, to unseat the valve, 40^a, which vents air directly from the train brake pipe, 53, to the atmosphere and causes an application of the brakes upon the car. Or, as shown in Fig. 11, the yielding strip may operate to close an electric switch, 38^a, and energize a magnet, 39^a, for opening the vent valve, 40^a, in the train brake pipe.

Another construction is shown in Fig. 12, in which the yielding strip, 56, is mounted on the car door, 55, by means of links, 57. A lever, 39^a, pivoted above the door has one arm extending in such position as to be engaged and actuated by the upward thrust of the strip, 56, and the other end of the lever is adapted to engage the stem of the pilot valve, 46^a, for opening same and causing the opening of the train pipe discharge valve, 50, as before described.

According to the modification shown in Figs. 13 and 14, the movable strip, 56, on the door is pivotally mounted on bell crank levers, 57^a, connected to a vertical rod, 58, which operates to partially rotate a longitudinal rod, 59, movable with the door and sliding through a square opening in a lever

arm, 84, as the door moves. The lever arm, 84, is connected by a link, 85, with a lever, 86, which operates the pilot valve, 46^b, for causing the opening of the train pipe discharge valve, 49. When the yielding strip, 56, is depressed by the door encountering a person or obstruction during its closing movement, the bell crank levers, 57^a, act to elevate the rod, 58, against the pressure of a spring, and through the connection with rod, 59, the latter is partially rotated, thus turning the levers, 84 and 86, and opening the pilot valve, 46^b. Compressed air from the train pipe, 53, is then discharged to the atmosphere by the opening of the vent valve, 49, for causing an application of the brakes as before described. It will be evident that any of these modified yielding strip constructions may also be used to operate the auxiliary valve, 40, if desired.

Having now described my invention, what I claim as new and desire to secure by Letters Patent is:

1. In a door operating apparatus, the combination with the door and a fluid pressure motor for actuating the same upon a car, of means operated by an object being forced against the door jamb, for controlling said motor and causing an application of the car brakes.
2. In a door operating apparatus, the combination with a car door and a motor for actuating the same, of a door jamb having a yielding strip, and means operated by the movement of said strip for controlling said motor and causing an application of the brakes upon the car.
3. In a door operating apparatus, the combination with a door and a fluid pressure motor for actuating same, of a main valve for controlling the pressure acting on said motor, an auxiliary valve governing said main valve, and means operated by an obstruction being caught in the door when closing, for actuating said auxiliary valve.
4. In a door operating apparatus, the combination with a door and a fluid pressure motor for actuating same, of valve mechanism for reversing the action of said motor, an auxiliary valve controlling said valve mechanism, and means operated by an obstruction being caught in the door when closing, for actuating said auxiliary valve.
5. In a door operating apparatus, the combination with a door and a fluid pressure motor for actuating same, of a valve mechanism for controlling the pressure acting on said motor and for causing an application of the brakes, an auxiliary valve governing said valve mechanism, and means operated by an obstruction being caught in the door when closing, for actuating said auxiliary valve.
6. In a door operating apparatus, the combination with a door and a fluid pressure

motor for actuating same, of a valve mechanism for causing an application of the brakes, an auxiliary valve governing said valve mechanism, and means operated by an obstruction being caught in the door when closing, for actuating said auxiliary valve.

7. In a door operating apparatus, the combination with a door and a fluid pressure motor for actuating same, of valve mechanism for reversing the action of said motor, an auxiliary valve controlling said valve mechanism, and a yielding strip adapted to be engaged by an obstruction in the doorway, for actuating said auxiliary valve.

8. In a door operating apparatus, the combination with a door and a fluid pressure motor for actuating same, of a valve mechanism for controlling the pressure acting on said motor and for causing an application of the brakes, an auxiliary valve governing said valve mechanism, and a yielding strip adapted to be engaged by an obstruction in the doorway, for actuating said auxiliary valve.

9. In a door operating apparatus, the combination with a car door and a motor for actuating same, of means operated by an obstruction being caught in the door when closing for causing an application of the brakes upon the car.

10. In a door operating apparatus, the combination with a car door and a motor for actuating same, of a train brake pipe having a valve, and means operated by an obstruction being caught in the door when closing, for causing the operation of said valve.

11. In a door operating apparatus, the combination with a car door and a motor for actuating same, of a train brake pipe, and means operated by an obstruction being caught in the door when closing, for venting fluid from said pipe to cause the brakes to be applied.

12. In a door operating apparatus, the combination with a car door and a motor for actuating same, of a yielding strip adapted to be engaged by an obstruction in the doorway, and means governed by the movement of said strip for effecting an application of the brakes upon the car.

13. In a door operating apparatus, the combination with a car door and a motor for actuating same, of a door jamb having a yielding strip, and means governed by the movement of said strip for effecting an application of the brakes upon the car.

14. In a door operating apparatus, the combination with a car door and a motor for actuating same, of a train brake pipe, a yielding strip adapted to be depressed by an obstruction caught in the door when closing, and means governed by the movement of said strip for venting fluid from said pipe.

15. In a door operating apparatus, the combination with a car door and a motor for

- actuating same, of a train brake pipe, a vent valve device therefor, a pilot valve for controlling the vent valve, and a yielding strip adapted to be depressed by an obstruction caught in the door when closing, for operating said pilot valve.
16. In a door operating apparatus, the combination with a car door and a motor for actuating the same, of a train brake pipe, a vent valve device therefor, a pilot valve for controlling the vent valve, a piston for actuating the pilot valve, an auxiliary valve for controlling the fluid pressure acting on said
- piston, and means operating said auxiliary valve when the door encounters an obstruction during its closing movement.
17. In a door operating apparatus, the combination with a car door and a motor for actuating the same, of means operating automatically upon the arrest of the door during the closing movement, for causing an application of the brakes upon the car.
